UNITED STATES PATENT OFFICE.

HUBERT McL. ARMISTEAD, OF SAN FRANCISCO, CALIFORNIA, ASSIGNOR TO MANIFOLD IMPRESSIONS CORPORATION, OF CARSON CITY, NEVADA, A CORPORATION OF NEVADA.

RIBBON-CARRYING ARM FOR MANIFOLDING TYPEWRITERS.

Application filed May 26, 1925. Serial No. 32,904.

My invention relates in general to manifolding typewriters, and in particular to that class of such machines, or attachments or parts thereof, which include one or more 5 pairs of spaced arms, each pair bearing a manifolding member stretched between their extremities, and adapted to be carried into and out of functional position in the line of type impact.

10 In such machines, the manifolding member is commonly an impression ribbon, the ends of which are fitted with clips adapted for ready connection with the arm extremities. It is essential that such ribbon be 15 stretched and held taut between its end fastenings. Various expedients have been adopted with this end in view, one of which particularly is to make the carrying arms laterally resilient, adapting them to hold the 20 ribbon under tension.

This, while serviceable in certain cases where no conflicting pressure or resistance is present tending to impair the arm resiliency, is not adequate in other cases, as, for 25 example, in those constructions wherein the arms play within laterally applied guides, since in describing their eccentric path, they must in moving down retire almost completely in said guides, in order to carry their 30 ribbon bearing extremities to the platen and place the ribbons in the line of type impact; and as at such time and in such position only the extremity of the arm projects from the guides, such extremity alone carries all 35 the effective tension resiliency, being confined thereto by the opposing guides, acting as stops to any useful tension effect. The arms thus become practically rigid at the 40 very time and in the very position in which their resiliency is most needed, namely in the line of type impact. This untoward effect is especially found in such cases wherein the arms play through guiding slots in a casing associated with the platen ends, said 45 arms in describing their eccentric path alternately retiring into and protruding from said casing, as, for example, in manifolding platens such as are disclosed in Patents Nos. 1,467,532 and 1,502,178 dated September 11, 50 1923 and July 22, 1924, respectively.

One of the objects of my invention is to obviate this difficulty by providing a novel carrying-arm of such form that the lateral

resiliency necessary for the functioning position of the ribbon is preserved unaffected 55 and unimpaired by the guides in which the arm plays. Again, in manifolding devices of the described type, the ribbon carrying arms have heretofore been made of relatively narrow, laterally resilient strips having angularly projecting free extremities to engage the end clips of the ribbons. The line of tension is, therefore, to one side of a direct line between the bodies of the arm pair which carries the ribbon, and this tends to torsion 60 in the arms, with the effect of producing unequal strain, relatively on the two edges of the ribbon, resulting in more or less lateral buckling of said ribbon, and departure 65 thereof from the flatness it should have in 70 order to yield its best impression.

Another object of my invention is to remedy this difficulty by providing a novel ribbon-carrying arm, of such form and so disposed in the general platen assembly that it 75 is not subject to such torsion stress.

Still another object of my invention is to provide a ribbon-carrying arm specially formed and so placed in the platen assembly, that it will not interfere with the full functional length of the platen member proper, and so mounted that it is adapted to carry 80 and hold the ribbon in close relation to the platen surface when it is moved to the line of type impact, but without any tendency of 85 the platen, in rotating, to disturb the true position of the ribbon.

Other objects will appear in the course of the following description.

I will state, at this point, that although 90 my improved ribbon-carrying arms are adapted for various assemblages of manifolding attachments for typewriters, they are especially intended for use in connection with the type of manifolding platens 95 disclosed in the patents above mentioned, and I shall, therefore, illustrate and describe them in connection with the platen of the later patent, using only so much of such platen as may be necessary for a full understanding of my improvement.

In the accompanying drawings to which reference may now be made—

Fig. 1 is a perspective view of one of my improved ribbon-carrying arms.

Fig. 2 is a perspective view showing a

pair of said arms with a ribbon stretched between them.

Fig. 3 is a view of a platen to which said arms are applied, the right hand end of the 5 platen being in longitudinal section in order to indicate the arm operating connections; the left hand end of the platen being in elevation, because such features as may be associated therewith, are immaterial to an understanding of my invention.

Fig. 4 is a section on the line 4—4 of Fig. 3.

Referring to Fig. 1, the carrying-arm indicated as a whole by the numeral 1 is a 15 laterally resilient metallic strip comprising a body portion *a* in which is a slot *b*, a pivotal foot portion *c*, a supplementally or independently laterally resilient head loop or return bend *d*, a clip-receiving member 20 *e*, and a body-widening extension portion *f*.

The head loop or return bend *d* extends laterally from the body *a* to one side of the extension *f*, and the clip receiving member *e* extends angularly from the free extremity 25 of said bend *d* in a return direction approximately parallel with and slightly higher than the top of the extension *f*.

In Fig. 2 a manifolding ribbon 2 is shown, with end clips 2'. These clips engage the receiving members *e* of the arms 1, and the ribbon passes over the top of the body-widening extension *f*, and by reason not only of the general resiliency of the arm body but also of the supplementally 35 resilient heads or bends *d*, said ribbon is held under tension between the two arms.

Referring now to Figs. 3 and 4, the platen comprises a shell 3 having the usual cushion covering 4.

40 Through the platen extends a shaft 5 having turning knobs 6.

Associated with the platen at each end, is a casing 7, which does not partake of the rotation of the platen, the latter being 45 mounted for independent rotation, by means of an internal bearing collar 8 journaled on a flange 9 of the casing 7, the flanges 9 of the two casings being connected by a tubular member 10.

50 Independently and severally rotatable about the platen shaft 5 and within the tubular member 10 is an assemblage of nested sleeves 11, here shown as three in number, the ends of said sleeves projecting 55 into the casing 7, and each carrying a crank arm 12 provided with an oppositely extending tail piece 13, Fig. 4, each of said tail pieces having a stud 14 which plays in and through a slot 15, Fig. 3, in a chamber 16 of the casing 7.

Upon the platen shaft 5 is mounted for independent rotation a prime operating member in the shape of a sleeve 17, having 60 connected at one end a knob 18 for turning it. The other end of the sleeve 17 extends

into the chamber 16 and carries fingers 19, which are adapted to act upon the studs 14 and turn the crank arms 12.

The details included but not shown in the closure indicated by 23 at the left hand end 70 of the platen in Fig. 3, by which the rotation of the platen is effected by the shaft 5; the details of control of the platen rotation for definite and variable line spacing, as operated by the lever 24, and the selective 75 operation of the crank arms 12, by which a plurality of ribbons are made possible need not be herein illustrated or described, as they form no part of my invention, and are not necessary to a complete understanding 80 of my improvements. It will be sufficient for my purpose to direct attention to the fact that the platen I have herein partly illustrated and described, is the platen of Patent No. 1,502,178 above mentioned, and reference may be had to it, though I consider such reference will not be necessary.

In the casings 7 are made the peripheral guide slots 20. Through these slots are 90 entered my ribbon carrying-arms 1, their foot portions *c* being pivoted at 21, Fig. 4, in the casing 7 in a line eccentric to the platen axis, and their slotted bodies being slidably connected at 22, as shown in 95 said Fig. 4, with the crank arms 12.

As indicated in Fig. 4, the ribbon-carrying arms 1 are thus adapted to be moved to carry their ribbons down to a line of type impact in front of the platen, and elevated to a position out of use, above and rearwardly of the platen, as shown by the full and dotted lines, respectively, the ribbon carrying arms 1 traveling in and sliding in and out through the peripheral guide slots 20 of the casings 7, the operation in this 100 respect being essentially the same as that of the patent referred to.

The objects and effect of my improvements may now be demonstrated.

In the ribbon carrying arms of the prior art, the resilient feature of said arms designed to hold the ribbon under tension is due to a general lateral springiness of their 110 entire length. It is obvious, however, that said arms playing in the guide slots 20 have their maximum resilience when protruding farthest from the casing, as in their elevated out-of-use position; and as they descend and retire into the casing their resilience decreases, due to the conflicting walls of the 115 slots, until when they arrive at their lower position, in the line of type impact, their effective resilience becomes practically nil. This is not as it should be, for it is in this latter position such resilience is most needed 120 in order to hold the ribbon under proper tension when in use.

In my carrying-arm 1, the lateral resilience due to the general length-springiness 125 is still present, in order to enable the 130

ribbon to be easily mounted but this resilience is supplemented by the spring loop or return bend *d* at the outer end of the arm, and as this loop or bend never in any 5 position enters the guide slot 20 but is, in all positions, outside thereof, it is not affected by said slot and its resilience is therefore made use of in holding the ribbon under tension in the line of type impact.

10 Again, in the relatively narrow carrying arms of the prior art with their angularly directed ribbon-clip receiving members, the line of ribbon stress lies to one side of the arm, and this tends to torsion in the arm, 15 which produces unequal tension on the sides of the ribbon inclining it to buckle or become distorted from a desirable flatness and smoothness.

In my improved arm, this is remedied by 20 the body-widening extension *f* underlying the plane of the ribbon, and centered with the line of ribbon tension, said extension being so placed on the arm body that it lies and plays in the slot 20 and is held against 25 torsion by the slot walls.

Although as far as the foregoing advantages of my improved ribbon-carrying arms are concerned, the spring-loops or bends *d* of said arms may be turned either inwardly, 30 over the platen, or as herein shown turned outwardly over the casing 7, I find that in the latter arrangement a two fold advantage is had, in that first the entire length of the platen is free from interference of the arms, 35 and that, second, by making the casings 7 of slightly smaller diameter than the platen, as shown in Fig. 3, the clip receiving extremities of the arms may be brought down to a slightly lower plane than the 40 surface of the platen thus bringing the ribbons down in very close relation to said platen, and since the casings 7 to which the arm extremities are brought down closely, do not rotate with the platen, there is no 45 tendency of the platen revolution frictionally disturbing said arms or the position of the ribbons when in use.

I claim:—

1. A ribbon-carrying arm for manifold- 50 ing typewriters comprising a strip, the body of which below one of its ends being widened to one side, and a ribbon-receiving member carried by said end and extending therefrom opposite to and spaced from the 55 widened body of the strip.

2. A ribbon-carrying arm for manifold- 60 ing typewriters, comprising a laterally re- silient strip having at one end a supple- mentally laterally resilient member, the body 65 of the strip below said member being widened to one side; and a ribbon-receiving member carried by said resilient member and extending therefrom opposite to and spaced from the widened body of the strip.

65 3. A ribbon-carrying arm for manifold-

ing typewriters comprising a strip, one of the ends of which is formed with a return bend resilient in a plane transverse to its axis of flexure, the body of said strip below said bend being widened to one side there- 70 of, and a ribbon-receiving member carried by the free extremity of said resilient bend and thence extending in a plane parallel with said axis opposite to and spaced from the widened body of the strip. 75

4. A ribbon-carrying arm for manifold- 80 ing typewriters comprising a slotted strip having at one end a foot adapted for the mounting of the arm for swinging move- ment, and at its opposite end a laterally re- silient return bend, the body of said strip 85 below the bend being widened to one side thereof, and a ribbon-receiving member carried by the free extremity of said resil- ient bend and thence extending opposite to and spaced from the widened body of the strip.

5. In a manifolding typewriter, the com- 90 bination of a platen; a manifolding ribbon associated therewith and adapted for move- ment to and from a position in the line of type impact; a pair of spaced arms associ- 95 ated with the platen and carrying the ribbon between their extremities, each of said arms comprising a laterally resilient strip hav- 100 ing at one of its ends a supplementally lat- erally resilient member and a ribbon re- ceiving member carried by said supplement- al resilient member; means for mounting each arm by its other end for swinging movement; fixed guides in which said arms have both arcuate and linear movement; and means for operating said arms. 105

6. In a manifolding typewriter, the com- 110 bination of a platen; a manifolding ribbon associated therewith and adapted for move- ment to and from a position in the line of type impact; a pair of spaced arms associ- 115 ated with the platen and carrying the ribbon between their extremities, each of said arms comprising a strip one of the ends of which is formed with a laterally resil- ient return bend and a ribbon-receiving mem- 120 ber carried by the free extremity of said resil- ient bend; means for mounting each arm at its other end for swinging movement; fixed guides in which said arms have both arcuate and linear movement; and means for operating said arms. 125

7. In a manifolding typewriter, the com- 130 bination of a platen; a manifolding ribbon associated therewith and adapted for move- ment to and from a position in the line of type impact; a pair of spaced arms associ- ated with the platen and carrying the ribbon between their extremities, each of said arms comprising a strip having one of its ends laterally resilient, the body of the strip be- low said end being widened to one side there- of and a ribbon-receiving member car-

ried by said end and extending therefrom opposite to and spaced from the widened body of the strip; means for mounting each arm at its other end for swinging movement; 5 fixed guides in which said arms have both arcuate and linear movement; and means for operating said arms.

8. In a manifolding typewriter, the combination of a platen; a manifolding ribbon 10 associated therewith and adapted for movement to and from a position in the line of type impact; a pair of spaced arms associated with the platen and carrying the ribbon between their extremities, each of said arms 15 comprising a strip one of the ends of which is formed with a laterally resilient return bend, the body of the strip below said bend being widened to one side thereof, and a ribbon-receiving member carried by the free 20 extremity of said resilient bend and thence extending opposite to and spaced from the widened body of the strip; means for mounting each arm at its other end for swinging movement; fixed guides in which said arms 25 have both arcuate and linear movement; and means for operating said arms.

9. In a manifolding typewriter having a platen with associated arm-guides and a manifolding ribbon adapted for movement 30 to and from the line of type impact; a pair of spaced laterally resilient arms carrying said ribbon, mounted for both arcuate and linear movement in said guides, the ribbon-carrying extremities of said arms lying beyond the guides and having supplemental laterally resilient members.

10. In a manifolding typewriter having a platen with associated arm-guides and a manifolding ribbon adapted for movement 40 to and from the line of type impact; a pair of spaced laterally resilient arms carrying said ribbon, mounted for both arcuate and linear movement in said guides, the ribbon-carrying extremities of said arms at their 45 outer ends beyond the plane of the ribbon

having a return bend resilient in a plane transverse to its axis of flexure.

11. In a manifolding typewriter having a platen with associated arm guiding slots and a manifolding ribbon adapted for movement 50 to and from the line of type impact; a pair of spaced arms carrying said ribbon, mounted for both arcuate and linear movement in said guiding slots, the ribbon-carrying extremities of said arms beyond the 55 plane of the ribbon being formed with a laterally resilient return bend and a ribbon receiving member extending to one side of said bend, and the body of the arm opposite said ribbon receiving member being widened 60 and adapted to coact with the guide slot to resist torsion stress in the arm and to hold the ribbon flat under equal tension.

12. In a manifolding typewriter having a platen with an associated peripherally 65 slotted casing at each end, and a manifolding ribbon adapted for movement to and from the line of type impact; a pair of laterally resilient spaced arms carrying said ribbon and mounted for movement in the 70 slots of the casings, said arms at their outer extremities being formed with supplemental laterally resilient portions extending in a direction away from the platen ends.

13. In a manifolding typewriter having a 75 platen; a peripherally slotted casing associated with each end of the platen and of smaller diameter than said platen; a pair of spaced arms mounted for movement in the slots of the casings, said arms at their outer 80 extremities being formed with laterally resilient bends extending in a direction away from the platen ends; and a manifolding ribbon carried by and between the resilient bends of said arms and adapted to be moved 85 to and from the line of type impact.

In testimony whereof I have signed my name to this specification.

HUBERT McL. ARMISTEAD.
